UNITED STATES PATENT OFFICE.

GUSTAV A. W. BARKOWSKY, OF GOWANDA, NEW YORK, ASSIGNOR TO
GOWANDA NOVELTY COMPANY, OF GOWANDA, NEW YORK.

SELF-IGNITING GAS-BURNER.

SPECIFICATION forming part of Letters Patent No. 735,196, dated August 4, 1903.

Application filed May 25, 1903. Serial No. 158,601. (No model.)

To all whom it may concern:

Be it known that I, GUSTAV A. W. BARKOWSKY, a subject of the German Emperor, and a resident of Gowanda, in the county of 5 Cattaraugus and State of New York, have invented new and useful Improvements in Self-Igniting Gas-Burners, of which the following is a specification.

This invention relates more particularly to 10 a self-igniting gas-burner of that type in which the gas is caused to impinge against an igniting body or substance which ignites the gas by reason of the contact of the latter with said material. Burners of this class are provided with a pilot-tube for directing the gas 15 against the igniting material and a controlling valve or cock by which the gas can be admitted to the pilot-tube and ignited, then directed to the burner and ignited from the pilot-flame, and then cut off from the pilot-tube. In order 20 to insure reliable, quick, and uniform action, the igniting material, which usually consists of a platinum sponge treated with certain chemicals, must be kept free or clean 25 from any of the ingredients or elements of the gas which would tend to clog or foul it. For that purpose a filter has been provided in the burner, through which the gas passes on its way to the pilot-tube.

One object of the present invention is to 30 still further prevent the clogging or fouling of the pilot-tube and igniting material by deposits of substances carried by the gas, and for that purpose the burner is provided with 35 means for opening the pilot-tube to the atmosphere when the gas is cut off, so that air can circulate freely through the pilot-tube at all times, except when the valve is shifted to admit gas to it for the purpose of igniting the 40 flame.

Another object of the invention is to guard 45 against leakage of gas into the pilot-tube.

Another object of the invention is to arrange the gas filter or purifier of the burner 50 in such manner that it is always in communication with the gas-supply and filled with gas, thus avoiding the delay caused in expelling air from the filter and insuring quicker and more certain action of the device.

Another object of the invention is to provide 55 the controlling valve or cock with operating

means which acts alternately to ignite and extinguish the flame at successive actuations of the device, thus making it unnecessary for a person using the burner to have any special 55 or intimate knowledge of its action.

In the accompanying drawings, Figure 1 is an elevation of a self-igniting gas-burner of the incandescent type embodying the invention, showing the position of the controlling- 60 valve and its actuating-lever when the burner is lighted. Fig. 2 is a fragmentary vertical section in line 2 2, Fig. 1. Fig. 3 is a fragmentary vertical section, on an enlarged scale, in line 3 3, Fig. 5, showing the valve in position 65 to admit gas to the pilot-tube. Fig. 4 is a horizontal section through the valve-chamber in line 4 4, Fig. 3. Fig. 5 is a transverse vertical section in line 5 5, Fig. 3. Fig. 6 is a horizontal section through the filter in line 70 6 6, Fig. 1. Fig. 7 is a bottom plan view, on an enlarged scale, of the valve detached. Fig. 8 is a fragmentary elevation showing the position of the valve when the gas is extinguished and also showing the valve-actuating 75 lever set ready to open the pilot and ignite the flame when it is next actuated. Fig. 9 is a cross-section of the valve in the position of the parts shown in Fig. 8. Fig. 10 is a vertical section through the trap-passage in 80 line 10 10, Fig. 4.

Like letters of reference refer to like parts in the several figures.

A represents the burner-tube of an ordinary 85 incandescent or other gas-burner, B the pilot-tube, and C a support or holder secured to the upper end of the pilot-tube and adapted to hold the igniting material above the upper end of the pilot-tube, so that the gas issuing from the latter will impinge upon and 90 be ignited by said igniting material. The igniting material may be of the character set forth in United States Letters Patent No. 668,367, issued to me February 19, 1901.

The burner and pilot tubes are secured in 95 any suitable manner to the upper portion of the burner base or body D, which is provided at its lower end with a screw-threaded nipple d for attaching it to a gas-supply pipe or fixture. The body D is provided with an annular filter or purifier chamber E, which communicates at its lower end by one or more 100

openings or ports *e* with the nipple *d*, so that the gas has access to the filter-chamber at all times. The filter-chamber contains a filtering material *F*, through which the gas percolates and which removes from the gas all liquid and solid matter which would gum or clog the pilot-tube and the igniting material. The impurities vary in different gases and the filtering material is so selected as to best 10 purify the particular gas being burned. A mixture of caustic soda and asbestos fiber or human hair produces good results.

The burner-body is provided above the filter-chamber with a chamber or seat *G* for the 15 valve or plug *G'*, which controls the burner-tube and pilot-tube.

H represents the lower part of the main gas - passage extending through the filter-chamber and connecting the interior of the 20 valve *d* directly with the valve-chamber.

H' represents the continuation of the passage through the upper portion of the burner-body and connecting the valve-chamber with the burner-tube.

25 *I* represents the inlet portion of the gas - passage, which connects the filter-chamber with the pilot-tube. The passage *I* is arranged on one side of the main gas-passage *H* and extends from the upper portion of the 30 filter-chamber to the lower portion of the valve-chamber or seat.

35 *J* represents a substantially U-shaped passage which is arranged in the burner-body below the valve-seat and which has a vertical portion *j*, which opens in the valve-seat, a vertical portion *j'*, which connects with the pilot-tube, and a horizontal portion *j''*. This passage, which descends from the valve-seat before it ascends toward the pilot-tube, forms 40 a trap, which prevents any gas which might leak into the valve-chamber from passing readily to the pilot-tube, for the gas being lighter than the air will not readily descend into the passage *J*.

45 The valve *G'* is preferably of the conical-plug type and is seated and adapted to turn in the valve chamber or seat *G*. The valve is provided with a transverse main passage *l*, which, in the position of the valve shown in 50 Fig. 2, connects the parts *H H'* of the main-gas passage, so that the gas can pass directly from the supply-pipe to the burner-tube. The plug is further provided with a passage *l'* of inverted-U shape which, in the position of 55 the plug shown in Figs. 3 and 5, connects the passage *I*, leading from the filter-chamber, with the trap-passage *J*, connecting the valve-chamber with the pilot-tube, so that the gas can pass from the filter-chamber to the pilot- 60 tube. The plug is also provided at its large end with a notch or recess *l''*, which extends inwardly from the end of the plug and connects the trap-passage *J* and the pilot-tube with the atmosphere in all positions of the 65 plug, except that shown in Figs. 3 and 5, in which the valve connects the filter-chamber with the pilot-tube. When the valve is in

the position shown in Figs. 8 and 9, the main or burner passage is closed, as well as the passage leading to the pilot-tube, so that no 70 gas passes to either the burner-tube or pilot-tube. In this position the air-passage *l'* of the plug places the pilot-tube in communication with the atmosphere, so that the air can circulate through the pilot-tube and clear the 75 same of gas, thereby preventing the deposit of impurities which would clog or foul the pilot-tube. When the gas is to be ignited, the valve is turned to the left to the position shown in Figs. 3 and 5, thereby connecting 80 the filter-chamber with the passage leading to the pilot-tube, so that gas passes from the filter-chamber through the pilot-tube and is ignited at the upper end of the latter by the igniting material. In this position of the 85 valve the air-passage does not connect with the pilot-tube. The valve is next turned partly to the right—that is, to the position shown in Figs. 1 and 2—which movement first connects the parts *H H'* of the main gas-passage, so that gas passes to the burner-tube 90 and is ignited from the pilot-flame. The continuation of this movement then cuts off communication between the filter-chamber and pilot-tube and extinguishes the pilot- 95 flame. The air-passage is at the same time connected with the pilot-tube, so that the latter is opened to the atmosphere. The valve 100 can be turned to the several positions indicated by an ordinary hand piece or lever secured to the valve, in which case some knowledge of or familiarity with the device would be required to properly operate the valve.

In order to simplify the manipulation of the valve, the following operating mechanism is preferably employed: *M* represents a spring which is secured at one end to the body of the burner. The free end of the spring bears against an arm *m* on the valve when the latter is in the position shown in Fig. 1. When the valve is turned to the left to ignite the pilot-flame, this spring *M* is strained, and when the valve is released the spring returns it to the position shown in Fig. 1 to ignite the burner-flame and extinguish 115 the pilot - flame. The spring is prevented from turning the valve farther to the right by a stop shoulder or projection *m'*, which the spring strikes. This spring acts automatically and prevents a person using the 120 burner from leaving the valve in the position in which the gas enters the pilot-tube while the burner is in operation.

N represents a valve-operating lever which is loosely mounted to swing on a pivot *n* at 125 one end of the valve. The lever is held on its pivot by suitable means, such as a nut and washer *n' n''*, and is preferably provided with a depending pull chain or cord *n'''*. The valve-lever is provided with a tailpiece or arm *O*, 130 which is adapted to engage with either of two pins *p p'*, projecting from the valve on opposite sides of said tailpiece.

Q Q' represent two springs which are se-

- cured at their lower ends to the burner-body and have their upper free ends arranged on opposite sides of the valve-lever and adapted to bear against the opposite sides thereof.
- 5 The springs are preferably secured to a dovetailed block q , which is removably held in a transverse dovetailed groove q' in the body of the burner. The springs may be secured to the burner in any other suitable manner, 10 or the described connection is desirable, as it permits the springs to be readily attached to and detached from the burner. When the valve is in the position shown in Fig. 8, in which the burner and pilot tubes are disconnected from the gas-supply passage, the 15 spring Q bears against the pin p on the valve, and its upper end is thereby held from exerting any pressure on the lever, which is held over to the left by the other spring Q' .
- 20 When it is desired to ignite the gas, the chain is pulled, which, on account of the position of the lever, swings the lever downwardly and toward the left. The tailpiece on the lever, which bears against the pin p' on 25 the valve, turns the latter and the valve to the left to the position shown in Figs. 3 and 5 and connects the pilot-tube with the filter-chamber. When the valve is thus turned to the left, the arm m on the valve engages and 30 strains the spring N , and as soon as the chain is released the said spring N returns the valve to the position shown in Figs. 1 and 2 to ignite the burner-flame and extinguish the pilot-flame. The movement of the valve to 35 the left is arrested when the valve is in position to connect the trap with the filter-chamber by the engagement of the arm m with a stop shoulder or projection q^2 on the burner-body. In this position of the valve the pin 40 p' on the valve engages the spring Q' and holds the latter from exerting any pressure on the lever, while the pin p on the valve is lowered out of engagement with the upper end of the spring Q , which then exerts its 45 pressure on the valve-lever and throws the latter over to the right, as shown in Fig. 1. In this position of the lever a downward pull on the chain will swing the lever downwardly to the right, so that its tailpiece will engage 50 the pin p on the valve and turn the latter to the position shown in Fig. 8 to extinguish the flame. The movement of the valve to the right is limited by co-operating stops r r' on the valve and burner-body, respectively.
- 55 When the lever is released, it is thrown over to the left by the spring Q' , as before explained. By the described mechanism for operating the valve it is impossible for a person to improperly operate the device, for when 60 the flame is extinguished the lever is in position to operate the valve to direct the gas to the pilot-tube and when the burner is in operation the lever is in position to extinguish the flame.
- 65 While the invention is described in connection with a self-igniting gas-burner involving a material which ignites the gas by

reason of the physical or chemical action of the same on the gas, it will be apparent that the improvements are applicable to burners 70 provided with a mechanical igniting device and that some of the described improvements are also applicable to other burners having a pilot-tube.

I claim as my invention—

1. In a gas-burner, the combination of a gas-supply passage, a pilot-tube, and a valve which in one position connects said pilot-tube with said gas-supply passage and in another position disconnects said pilot-tube and gas-supply passage and opens said pilot-tube to the atmosphere, substantially as set forth. 75

2. In a gas-burner, the combination of a burner-tube, a pilot-tube, a gas-supply passage, and a valve which in one position connects said pilot-tube with said gas-supply passage, and in another position disconnects said pilot-tube from said gas-supply passage, connects said burner-tube with said gas-supply passage, and also opens said pilot-tube 85 to the atmosphere, substantially as set forth. 90

3. In a gas-burner, the combination of a body, a valve-chamber in said body, a gas-supply passage, a pilot-tube, a passage leading to said pilot-tube, and a valve which in 95 one position connects said gas-supply passage and said passage leading to said pilot-tube, said valve having a passage which connects said pilot-tube with the atmosphere when said pilot-tube is disconnected from 100 said gas-supply passage, substantially as set forth.

4. In a gas-burner, the combination of a body, a burner-tube, a pilot-tube, a filter-chamber, a gas-supply passage with which 105 said filter-chamber connects, a passage leading from said filter-chamber to said valve-chamber, a passage leading from said valve-chamber to said pilot-tube, and a valve in 110 said valve-chamber which in one position connects said gas-supply passage and said burner-tube and in another position connects said passage leading from the filter-chamber with the passage leading to said pilot-tube, said valve having a passage which 115 connects said pilot-tube with the atmosphere when said valve is in position to disconnect said filter-chamber from said pilot-tube, substantially as set forth. 120

5. In a gas-burner, a body provided with a main gas-supply passage, a pilot-tube, and a valve having a main passage for connecting the parts of the main gas-passage, a secondary passage for connecting the gas-supply passage with the pilot-tube, and an air-passage 125 for connecting the inlet end of the pilot-tube to the atmosphere, substantially as set forth.

6. In a gas-burner, the combination of a gas-supply passage, a filter, a pilot-tube, a 130 valve-chamber, a passage leading from said filter to said valve-chamber, a trap-passage connecting said valve-chamber and said pilot-tube, and a valve, substantially as set forth.

7. In a gas-burner, the combination of a pilot-tube, a gas-supply passage, an oscillating valve controlling said gas-supply passage and said pilot-tube, a valve-operating device 5 movable independently of the valve, and a spring mechanism which acts automatically to throw said device alternately to different positions, whereby said device and valve are turned in opposite directions by successive 10 operations of said device, substantially as set forth.
8. In a gas-burner, the combination of a gas-supply passage, a pilot-tube, an oscillating valve controlling said gas-supply passage 15 and pilot-tube, a valve-operating lever movable independently of said valve, a part connected to said valve and which is engaged by said lever to turn the valve in one direction, a part connected to said valve and which is 20 engaged by the lever to turn said valve in the opposite direction, and a spring mechanism for automatically moving said lever to alternately engage said parts connected to said valve, substantially as set forth.
9. In a gas-burner, the combination of a 25 body provided with a gas-supply passage, a pilot-tube, an oscillating valve controlling said gas-supply passage and said pilot-tube, an oscillating valve-operating lever, a projection 30 on said valve which is engaged by said lever to turn said valve in one direction, a projec-

tion on said valve which is engaged by said lever to turn said valve in the opposite direction, and springs which act on said lever in opposite directions to swing the latter alternately to opposite sides of a central position, said projections coöoperating with said springs to alternately hold said springs from exerting their action on said lever, substantially as set forth. 35

10. In a gas-burner, the combination of a body provided with a gas-supply passage, a pilot-tube, an oscillating valve controlling said gas-supply passage and said pilot-tube, a valve-operating lever pivoted to swing independently of said valve, a projection on said valve which is engaged by said lever to turn said valve in one direction, a spring which acts to turn said valve partially in the opposite direction, a second projection on said 45 valve which is engaged by said lever to turn said valve farther in said second direction, and springs which act to move said lever in opposite directions and with which said projections on said valve coöperate to alternately 50 prevent the action of said springs on said lever, substantially as set forth.

Witness my hand this 23d day of May, 1903.

GUSTAV A. W. BARKOWSKY.
